UNITED STATES PATENT OFFICE.

WILLIAM HOWD, OF ST. LOUIS, MISSOURI.

STOVEPIPE-ELBOW.

1,101,283.

Specification of Letters Patent. Patented June 23, 1914.

Application filed February 28, 1914. Serial No. 821,631.

To all whom it may concern:

Be it known that I, WILLIAM HOWD, a citizen of the United States, and a resident of St. Louis and State of Missouri, have made and invented certain new and useful Improvements in Stovepipe-Elbows, of which the following is a specification.

My invention relates to a new and useful improvement in stove-pipe elbows, and more particularly to an elbow so constructed that the connecting stovepipe may be easily cleaned without necessitating the removal of the elbow.

An object is to provide an elbow so arranged that the cleaning or scraping implement may be kept within the elbow and only a portion of the handle protrude therefrom, and at the same time the scraping implement in such a position that the draft will be in no way affected.

Still another object is to provide an elbow so constructed that the connecting pipe may be easily cleaned without necessitating the removal of the elbow, and at the same time obviate all danger of soot flying into the face of the operator or out into the room. Heretofore as far as I am aware some stovepipe elbows have been constructed with a door or passageway in the center of the elbow, but it is necessary to keep this door open while the operator is cleaning or scraping the stovepipe, and as the door over the opening has to be large enough for the insertion of the scraping implement the soot or dust or products of combustion are apt to fly into the room, especially if the scraping action is at all violent. In this form of construction also the elbow might only be cleaned when there was no fire in the stove as the draft would be seriously affected and the smoke or gases would tend to be discharged into the room. With the present form of elbow herein shown and to be hereinafter fully described, the elbow or pipe may be readily cleaned regardless of whether there is a fire in the stove below, and the danger of soot or products of combustion or gases entering the room is obviated; and the scraper or cleaning implement may be left in the elbow but in no way interfering or affecting the draft.

With these and other objects in view my invention consists in certain new and novel features of construction and combination of parts as will be hereinafter fully described and pointed out in the claims.

In the drawings Figure 1 is a view in elevation of my improved elbow and a portion of a pipe shown in section. Fig. 2 is a perspective view of a portion of my improved elbow showing the door in an open position. Fig. 3 is a sectional view of my improved elbow showing the scraper in its outward position and Fig. 4 is a perspective view of the scraper.

Referring now to the drawings, an elbow 1, is shown having on its outer surface an aperture 2, the same being semi-circular in outline, and hinged at one side of said aperture is a door 3 of the same general outline it of course being somewhat larger than said aperture, so that said aperture will be entirely closed when the door is in its closed position. In this door 3 is formed a small opening 4, which opening is preferably formed by striking inwardly a portion of the metal of the door to form a lip or rest

5. In a position slightly above said opening 4 is pivoted a small cover 6 that may be swung over said opening 4 if for any reason so the scraping implement to be hereinafter described is removed from its position within said elbow. Also pivoted to the door 3 and opposite the hinge is a retaining or latch member 7 that is adapted to engage with 80 the stud 8 secured to the elbow 1.

In Fig. 4 is clearly shown a scraper 9 provided with a handle 10, and the blade of this scraper is preferably semi-circular in shape and provided with the flange 11 so that it 90 will slide easily on the inner surface of the elbow and the connecting pipe, during the cleaning operation. The handle 10 of the scraper may be of any desirable length and the outer end thereof is preferably screw-threaded as shown at 12, so that the gripping member or handle 13 may be secured thereto. It will be understood that by constructing the scraper in this manner that if for any reason an extra long handle was needed an 100 extension might be provided that would have a socket on one end to engage the screw threads 12, and on its other end be provided with screw threads that would fit into the socket of the gripping member 13.

To assemble the various parts after the elbow is set in its fixed position the door 3 is opened, the gripping member 13 is removed from the handle 10 and the scraping member is inserted through the opening or 110 aperture 2 of the elbow 1. The handle 10 would then be inserted through the opening

4 and the gripping member 13 then secured to the handle 10. The door 3 is then closed and the retaining or latch member 7 passed over the stud 8. The scraping member 9 is 5 then pulled outwardly as clearly shown in Fig. 3, and slightly tilted so that the upper edge of the scraper 9 rests against the inner surface of the elbow 1, the handle 10 resting on the lip 5 and against the upper edge 10 of the opening 4. By thus providing the three points of contact the scraper is held securely in position, until moved by the operator, and at the same time in such a position as it in no way affects the draft of the 15 stove.

From the foregoing it will be seen that the scraper is always in its proper place; is readily accessible and at the same time in no way interferes with the draft. It will also 20 be seen that the main door 3 does not have to be opened except for the insertion of the scraper, and does not have to be opened thereafter except that if for any reason it should be desired to insert a new scraper. 25 It will also be apparent that by so constructing my improved elbow, the door 3 may be always kept in a closed position and all danger from gases entering the room from the stove below or the soot dislodged by the 30 scraper during the process of cleaning absolutely prevented from flying into the face of the operator or in any way entering the room.

Having thus described my invention, what 35 I claim as new and desire to secure by Letters Patent, is:

1. A stove-pipe elbow provided with an opening in the outer surface thereof, a door

hinged to one side of said opening and adapted to close the same, said door provided with a relatively small opening, and a lip formed at the lower edge of said opening and fastening means for said door to hold the same in its closed position. 40

2. A stove-pipe elbow provided with an opening in the outer portion thereof, a door hinged at one side of said opening and adapted to close the same, said door provided with a relatively small opening, a support located just below said opening; a 45 scraper adapted to enter the opening in said stove-pipe elbow, the handle of which is adapted to pass through the opening in said door and be held by said support, and means for holding said door in its closed 50 position.

3. A stove-pipe elbow provided with an opening therein, a door hinged at one side of said opening and adapted to close the same, said door provided with a relatively 55 small opening and a lip formed at the lower edge of the same; and a scraper adapted to pass through the opening in said stove-pipe elbow, the handle of which is adapted to pass through the opening in said door and rests on said lip and against the upper edge 60 of the opening in said door to thereby hold said scraper in contact with the upper surface of said stove-pipe elbow. 65

Signed at St. Louis and State of Missouri 70 this 19th day of February, A. D. 1914.

WILLIAM HOWD.
